UNITED STATES PATENT OFFICE

106,154

DESIGN FOR A RAIL CAR OR SIMILAR VEHICLE

William B. Stout, Detroit, Mich., assignor to Pullman-Standard Car Manufacturing Company, a corporation of Delaware

Application August 10, 1935, Serial No. 58,065

Term of patent 7 years

To all whom it may concern:

Be it known that I, William B. Stout, a citizen of the United States of America and a resident of Detroit, county of Wayne, and State of Michigan, have invented a new, original, and ornamental Design for a Rail Car or Similar Vehicle, of which the following is a specification, reference being had to the accompanying drawing, forming a part thereof, wherein

Fig. 1 is a side elevation of a rail car embodying my design;

Fig. 2 is a plan view of the same;

Fig. 3 is an end elevational view;

Fig. 4 is a diagrammatic outline of a section through the mid-section of the car showing the cross sectional shape;

Fig. 5 is a front elevational view;

Fig. 6 is a perspective view of the car, the point of view being in front of the car; and

Fig. 7 is a perspective view, the point of view being in rear of the car.

I claim:—

The ornamental design for a rail car or similar vehicle substantially as shown.

WILLIAM B. STOUT.
